(57) **CLAIM**

The ornamental design for a combined container for fluids with a cap as shown and described.

DESCRIPTION

1. Combined container for fluids with cap

1.1 is a bottom plan view of a combined container for fluids with cap showing our new design;

1.2 is a front side elevation view thereof;

1.3 is a left side elevation view thereof;

1.4 is a perspective view thereof;

1.5 is a rear side elevation view thereof;

1.6 is a right side elevation view thereof;

1.7 is a top plan view thereof;

1.8 is a cross-sectional view thereof taken at line 1.3-1.3 in Fig. 1.3.

The design shows a combined container for fluids with cap, namely ink or solvent for an inkjet printer, with a cap. The dash-dot broken lines are directed to environment and form no part of the claimed design. The dash-dash broken lines in Fig. 1.1 depict the bounds of the claimed design and form no part of the claimed design.
